UNITED STATES PATENT OFFICE

FRANK D. HOWE, OF CUYAHOGA FALLS, OHIO

FURNACE

Application filed April 5, 1926. Serial No. 99,738.

This invention relates to devices for burning solid fuel, more particularly bituminous or other coal.

Among the objects of the invention are the securing of complete and smokeless combustion, small waste of unburned fuel, easy access to the fire for cleaning, and visibility of the fire, giving the effect of an open fire, with the efficiency of a closed fire.

The novel features are the means for charging the furnace with fuel at the rear, pushing the fuel forward by means of the swinging loader upon the forward tilted front grate, and the return of the grate to the vertical position to crowd the live coals back upon the fresh fuel so that ignition of gases as they distill off is assured and a bright, smokeless combustion is secured in that part of the furnace nearest the glass doors. Other novel features are the upper forwardly tapered grate bars and the lower bars pivoted at their rear and diverging from the upper bars forwardly and adapted to be shaken at their front ends, the floating, hollow air supply plate, the dumping hearth, the means for regulating air supply to the rear part of the grate, the construction of the glass doors by which expansion of the parts is prevented from breaking the glass, the baffles by which smoke is deflected away from the glass doors, the means for operating the parts and the general arrangement and relation of the parts.

Of the accompanying drawings:

Figure 1 is a vertical section through a furnace embodying the invention in a fireplace setting;

Figure 2 is a plan section through the plane —2—2— of Figure 1;

Figure 3 is a fragmentary outside view showing control parts;

Figure 4 is a fragmentary plan view of grate and control parts;

Figure 5 is a section on the plane —5—5— of Figure 4;

Figure 6 is a fragmentary front view of the glass doors;

Figure 7 is an enlarged section through Figure 6 on the plane —7—7—;

Figure 8 is an elevation, partly in section, of a modified form of the invention; and Figure 9 is an elevation showing a partial section on the plane —9—9— of Figure 8.

Referring to Figures 1 to 6 of the drawings, A is the fire box, or combustion chamber, in the front wall of which is an opening closed by doors, B, glazed with mica, heat resisting glass or other transparent substance, C. The rear wall of firebox A opens into a loading chamber D, in which is pivoted the loader E. A hinged cover F gives access to the loader. The top wall of the loader chamber should be raised above the radius of the loader as at D¹ to allow gas to pass into the fire box when the loader is raised.

Forward of the loader, in the bottom of fire box A, are the upper grate bars G on which the fuel rests, and the lower shaking bars H, described more fully later. Adjacent the front end of the upper grate bars is the swinging vertical grate I. The lower front wall A¹ of the fire box is shown as being made of brick. A hinge plate K is built into the wall and carries the hearth plate L, which is adjustable by lever M shown in Figures 3 and 4. An opening in the wall A¹ has a draft slide O, which controls the admission of air to the ash pit P.

Attached to the top wall of fire box A is the transverse baffle A² to keep the smoke away from the doors B, and the top wall is incurved as at A³ for the same purpose. Just forward of the loader E is a gas deflecting and auxiliary air feeder plate Q extending across the fire box and freely pivoted on hollow bearings Q¹. A stop Q² limits the downward motion of plate Q. A suitable damper Q³ may be employed to regulate the flow of air from plate Q. R is the smoke flue.

The grate bar construction is shown in Figures 1, 4 and 5. The upper set G is stationary and supported by cross members S and T. These bars are tapered forwardly to be of less width at their forward ends to avoid wedging of the fuel as it is shoved forward, and to provide increased air opening from the ash pit at the front as shown at G¹, G¹ where combustion is most rapid. Their front ends are given an upward inclination as at 100

G² to guide the forward moving fuel upon the inclined front grate. The lower set H, the bars of which are staggered with respect to those of the upper set G, is supported near the rear end on cross member S, which is notched to receive bars G and H and to hold them in proper spaced relation, and at the front end by shaker bar U, which is notched to receive the vertical flanges of bars H. Bar U extends through the fire box wall and the casing wall W, and is operated in any convenient way as by lever V. The bars H preferably slope forwardly slightly to increase the air opening at H¹ and facilitate clearing of ashes when shaken. The space between member S and rear wall A⁴ of the fire box may be open or closed by the adjustable plate X.

The loader E may be operated by being attached to a shaft E¹ journaled in the side walls of loader chamber D and operated in any convenient manner. To secure easy operation, any suitable mechanism may be employed. As shown in Figures 3 and 4, lever E², keyed to shaft E¹, has journaled at its outer end a pinion E³ and a ratchet wheel E⁴. On the shaft E⁵, to which the pinion and ratchet wheel are attached, is journaled a lever E⁶ having a pawl E⁷ engaging the ratchet wheel E⁴. The pawl E⁷ can be reversed so as to operate the ratchet wheel and pinion in either direction. Rigidly attached to the side of loader chamber D is a gear sector E⁸ with which pinion E³ engages. Oscillating lever E⁶ will move lever E² in one direction or the other, depending on the position of the pawl and the loader moved accordingly.

Front grate I is operated through shaft I², lever I³ and hand lever I⁴. Lever I³ carries a pawl I⁵ which engages with and is wider than ratchet plate I⁶, and also pin I⁷, which serves as a fulcrum for lever I⁴. Hand lever I⁴ has a notch in the lower end which engages pin I⁷, and also has a pin I⁸, which contacts the side of lever I³ to elevate the grate and engages the lower inclined surface of pawl I⁵ to disengage it as lever I⁴ is moved forward. Further movement of lever I⁴ brings pin I⁷ into contact with lug I⁹ on lever I³ and rocks grate I forward.

The device, as described above, may be used as a stove, as a steam or hot water boiler, or have an outer casing on the hot air furnace principle. As shown, it is a hot air furnace with a casing in the form of a fireplace, with brick side walls W, a metal front wall W², air inlet openings W³, near the floor, and outlets W⁴ near the ceiling. The rear walls of the furnace and smoke flue are shown exposed to radiate heat from the rear of the furnace and filler strips W⁵ (Figure 2) complete the casing at the rear.

Referring to Figure 7, in which the door is shown in detail, Y represents the outer

frame, Y² an inner frame, Y³ glass or other transparent material, and Y⁴ a metal channel in which the glass rests and which holds the pieces in place if the glass should be accidentally broken. These parts should be so fitted that the glass is free to adjust itself to expansion and contraction.

In the operation of the device shown in Figures 1 to 6, the fire is started next to the front grate, the latter being in the forward dotted line position, and the balance of the fuel grate filled with fuel. As the fire becomes established, there will be a zone of bright coals in front, a coking zone with a gas fire or flame zone at the rear of the coke fire and a mass of unignited coal at the rear of the flame zone. When more fuel is needed, the loader is brought to the vertical position, fuel is put into the loader chamber and the loader pushed downward and forward, forcing forward the fresh fuel and that on the grate bars. If a full charge of fuel is desired, front grate I is tilted forward and the fire pushed out upon it. Raising the grate forces the fire back upon the fresh fuel producing a practically smokeless fire. Where a moderate fire is desired, slack coal works better than lump. Clinkers and slate work forward against the front grate without wedging between the grate bars and can be pulled over onto the hearth plate L and dropped into the ash pit. Plate L may be held open to check the fire. The plate X, at the rear of the grate bars, is generally closed and is opened to drop ashes or to provide extra air for combustion. The auxiliary air feeder Q floats on the fuel and guides any gases formed below it forward toward the fire. The air emerging from the slot assists in this and also aids combustion.

In Figures 8 and 9, the twin arrangement shown is intended to be placed in the wall between two rooms in each of which an open fire effect is desired. Parts having the same functions as in the other type are given the same letter with the addition of an exponent "x". This furnace has two loaders E^x receiving fuel through doors F^x which may be duplicated in each room. G^x and H^x are the grates and I^x the vertical grates operated by lever I³⁴. They are at the sides of the fire. There are glass doors in each room. All controls are in duplicate so that the fire may be attended to in either room. The operation is the same as for the single furnace, except that the two loaders are used so as to keep the active fire at the center of the furnace.

Modifications of the invention may be resorted to without departing from the spirit thereof or the scope of the appended claims.

What is claimed is:

1. A furnace, one wall of which is transparent, said furnace including a grate, said furnace having an inlet and means associated therewith for feeding fuel horizontally

onto the grate at a point remote from the transparent wall whereby a zone of substantially smokeless combustion is produced adjacent said wall, and a movable abutment 5 cooperating with the grate adjacent said transparent wall for forcing burning fuel back upon the fresh fuel and for facilitating heaping of the fuel upon the grate.

2. A furnace, one wall of which is transparent, said furnace, including a grate, said furnace having an inlet and means cooperating therewith for feeding fuel horizontally onto the grate at a point remote from the transparent wall whereby a zone of substantially smokeless combustion is produced adjacent said wall, and a member pivoted to cooperate with the grate adjacent said transparent wall and movable between a position extending forwardly of the grate and an up- 10 right position so as to be operable to facilitate placement and combustion of the fuel upon the grate by receiving coals forced thereon during loading operation and forcing the fuels received thereon back upon the 15 fuels on the grate.

3. In a furnace having a transparent wall, a grate, means for feeding fuel horizontally onto the grate at a point remote from said wall, and a smoke baffle extending down- 20 wardly from the top of the furnace in back of said transparent wall.

4. In a furnace, a grate, said furnace having an inlet and means associated therewith for feeding fuel horizontally onto one end of 25 the grate, a hollow deflector plate pivoted at the top of the inlet and riding upon the fuel adjacent the feeding means, and means to supply air through the deflector plate over the fuel.

5. The combination in a furnace having a wall of its combustion chamber of transparent material, said wall being of substantial extent to provide the effect of a fireplace, of a grate in the bottom of the combustion 35 chamber, means for creating a draft from below the combustion chamber up through the grate, said furnace having an inlet remote from said transparent wall and means associated with the inlet to force fresh fuel 45 horizontally onto the grate and thereby to force the burning fuel in said furnace toward said transparent wall upon each feeding of fresh fuel into the furnace whereby a zone of substantially smokeless combustion 50 will be established in said furnace adjacent said transparent wall.

6. The combination in a furnace having the front wall of its combustion chamber of transparent material, said wall being of substantial extent to provide the effect of a fire place, of a grate in the bottom of the furnace, means creating a draft from below up through the grate, the rear wall of said furnace having an inlet therein through 55 which fresh fuel may be forced onto the

grate to push the burning fuel on the grate forwardly toward said transparent wall.

7. A furnace as claimed in claim 6, including an abutment associated with the front end of the grate and spaced from said transparent wall to limit the forward movement of the burning fuel when fresh fuel is being forced onto the grate.

8. The combination in a furnace of a grate, means for forcing fuel onto the grate from one end thereof, and a movable abutment member at the other end of the grate, said member being movable between a position extending outwardly of said end of the grate and a position substantially perpendicular to the grate whereby burning fuel forced outwardly on the extended abutment member may be crowded back upon the fresh fuel.
